UNITED STATES PATENT OFFICE.

JOHN J. JENNINGS, OF REIDVILLE, SOUTH CAROLINA.

NUT-LOCK.

No. 852,841.

Specification of Letters Patent.

Patented May 7, 1907.

Application filed January 7, 1907. Serial No. 351,200.

To whom it may concern:

Be it known that I, JOHN J. JENNINGS, a citizen of the United States of America, and a resident of Reidville, in the county of Spartanburg and State of South Carolina, have invented certain new and useful Improvements in Nut-Locks, of which the following is a specification.

This invention relates to that class or type of nut locks in which a nut has a divided part that projects from the face of the nut, such part carrying a second nut which may be adjusted upon the divided part, to compress the same upon the threads of the bolt to provide a secure lock, and my invention not only provides means for effecting such a lock, but; also includes means whereby the removal or separation of the compressing-nut from the bolt-engaging-nut is prevented, as will be hereinafter set forth.

In the accompanying drawings Figure 1 is a sectional view, showing the bolt-engaging-nut and the compressing-nut as applied to a bolt, Fig. 2 is a side elevation. Fig. 3 is a face or front view, and Fig. 4 is a side elevation, the compression-nut being shown in section.

The bolt A is of ordinary construction, and the nut B, which is internally threaded to engage the threads of the bolt may be of less thickness than the standard nuts, and from the front or face of the nut B there projects a neck b, the same having internal threads, the same as those of the nut, the exterior of the neck is tapered or conical and diminishes in diameter from the face of the nut B outward, the neck b is externally threaded and is provided with a plurality of slits or kerfs b' which extend from the outer end of the neck 40 to the face of the nut.

By the construction shown the bolt-engaging-nut and its externally tapered neck are internally threaded before the slits are formed in the neck, and either prior or subsequent to the slitting or kerfing of the neck the external threads are formed, and such threads may be of the same gage or pitch as the threads of the bolt. By internally threading the neck the nut B will have a greater bolt engaging surface than is usual, and the width of the nut proper may be less than nuts as usually manufactured.

The compression-nut C has a tapered open-

ing or bore which is threaded to correspond with the threads upon the neck, and in practice the compression-nut will engage the external threads on the neck b when positioned at the outer end of the neck, and the compression-nut C has formed in its outer face a recess c. When the compression-nut C has been placed upon the neck b of the bolt-engaging-nut B, the outer end of the neck is upset or spread outward to provide a flange b'', which will enter the recess c when the compression-nut is at the outer end of the neck, and when so positioned the divisions of the neck will not be compressed, the bolt-engaging-nut will be free to move upon the bolt and the sides of the nuts will be in line one with the other. The flanging or upsetting of the end of the neck prevents removal of the compression-nut either when on or off of the bolt and serves to maintain the sides in alinement so that the jaws of a wrench will engage both nuts to turn the same in unison, in screwing the bolt-engaging-nut on or off the bolt, and when the bolt-engaging-nut has been screwed home the wrench may be moved to engage solely the compression-nut and it can be moved upon the neck to cause the sections of the neck to jam upon the threads to securely lock the nut upon the bolt.

The bolt-engaging-nut and the compression-nut may be furnished to the trade with internal threads of standard gage, as an article of manufacture, and the nut B is not weakened by being slit. In use the nut C, may be forced toward the outer face of the nut B, to give the desired amount of friction between the threads of the bolt and the neck, and when the compression-nut is screwed to the outer end of the neck; the nuts may be removed from the bolt in the usual manner.

The combined inclined surfaces of the threads and tapered neck, and the leverage of the wrench will effect such a strain that the nut will be held on the bolt so as to provide a secure and positive lock, and when the nuts are of small size two opposite slits will be sufficient, whereas with larger nuts four slits are preferable.

I claim.

A bolt-engaging-nut having a tapered extension which is externally threaded; the nut

and its extension both being internally threaded, longitudinal slits through the extension and outward extending flanges on the outer ends of the divisions of the extension, a compression-nut having internal threads for engagement with the external threads of the extension of the bolt-engag-

ing-nut and a circumferential recess in the outer face of the compression-nut, substantially as shown.

JOHN J. JENNINGS.
